Des. 242,042

Patented Oct. 26, 1976

242,042

WATER SOFTENER CABINET

William J. Marsh, Racine, Wis., assignor to Saxton Water Conditioning Equipment, Inc., Santa Ana, Calif.

Filed Aug. 11, 1975, Ser. No. 603,365

Term of patent 14 years

Int. Cl. D23—01

U.S. Cl. D23—3

FIG. 1.

FIG. 2.

FIG. 1 is a perspective view taken from the front, top and left side of a water softener cabinet embodying my new design;

FIG. 2 is a right side elevational view thereof; and
FIG. 3 is a top plan view thereof.

The rear is plain and unornamented, except for a rectangular panel shown in FIG. 1, as indicated by FIGS. 2 and 3.

I claim:

The ornamental design for a water softener cabinet, as shown and described.
